UNITED STATES PATENT OFFICE.

MAX SCHWENDNER, OF READING, PENNSYLVANIA.

WRENCH.

No. 864,806.

Specification of Letters Patent.

Patented Sept. 3, 1907.

Application filed February 6, 1907. Serial No. 355,988.

To all whom it may concern:

Be it known that I, MAX SCHWENDNER, a citizen of the United States of America, and a resident of Reading, in the county of Berks and State of Pennsylvania, have invented certain new and useful Improvements in Wrenches, of which the following is a specification.

This invention relates to certain new and useful improvements in wrenches of that class embodying a movable jaw mounted for rocking movement on the shank of the stationary jaw, with a spring disposed within a recess of the movable jaw and acting against the shank of the stationary jaw.

The present invention has for its objects among others to provide an improved wrench of this general character which shall be simple and cheap, yet durable and efficient in use.

It has for a further object to provide such a construction that when the parallel portions of the shank and the movable jaw are held in parallel relation the wrench is securely locked in its adjusted position. The distance between the acting toothed face of the movable jaw and the acting portion of the opposite portion and of the guide pin is the same as the width 25 of the shank of the stationary jaw, so that when the movable jaw has been adjusted and its teeth are engaged in the teeth on the shank of the stationary jaw the parts are held in parallelism and the movable jaw firmly locked against movement. This arrangement further 30 relieves the movable jaw of the strain and also of the wear, the latter coming on the shank of the stationary jaw.

The movable jaw is formed with a curved portion forming a thumb rest by which the movable jaw may 35 be easily moved to its required position. This may be serrated if desired to insure a better hold.

The spring within a cavity of the movable jaw is held in place and rendered adjustable by means of a screw which extends from the outside of the jaw and accessible from the outside for the purpose of adjustment or removal, as may be desired.

The acting face of the stationary jaw is slightly inclined from a right angle to the face of the shank so as to provide a tapered opening between the jaws, which 45 insures a firm, solid grip on the nut or other article, and prevents slipping and all lost motion.

The teeth are made very fine so as to provide accurate adjustment, and the movable jaw is so easily movable as to permit of ready adjustment by the thumb 50 while handling the wrench with the hand.

Other objects and advantages of the invention will hereinafter appear and the novel features thereof will be specifically defined by the appended claims.

The invention is clearly illustrated in the accompanying drawings, which, with the numerals of reference 55 marked thereon, form a part of this specification, and in which

Figure 1 is a perspective view of my improved wrench. Fig. 2 is an enlarged detail partly in elevation and partly in longitudinal section. Fig. 3 is a 60 perspective view, on an enlarged scale, of the movable jaw removed from the shank.

Like numerals of reference indicate like parts throughout the several views.

Referring to the drawings, 1 designates the shank of 65 the stationary jaw, having the parallel-sided rectangular portion 2 integral with one end of which is the stationary jaw 3. This rectangular portion 2 is formed with a shoulder 4 for a purpose which will be herein-after made clear. One face of the rectangular portion 2 70 is toothed, as at 5, the teeth being fine so as to permit of very accurate adjustment. The acting face of the jaw 3 is slightly beveled or inclined with relation to a right angle from the face 7 of the rectangular portion 2, as seen at 6 in Fig. 2, for a purpose which will hereinafter 75 appear.

8 is the movable jaw. Its acting face 9 is exactly at right angles to its face 10 which is provided with fine teeth 11, as shown, for co-operation with the teeth 5 of the rectangular portion 2 of the shank 1. This face 10 is 80 upon a portion 12 which extends beyond the face of the jaw 9, the shoulder 13 serving as a stop to engage the shoulder 14 upon the inner face of the jaw 3. The movable jaw is formed with a recess 15 within which is the abutment 16, against which latter bears one end of a 85

spring 17, the other end of which is designed to bear against the outer face of the portion 2 of the shank, the said spring being detachably and adjustably held in position by means of the screw 18 which is inserted from the outer face of the jaw, with its inner end bearing 90 against said spring opposite said abutment, as shown clearly in Fig. 2. By this means the spring is readily controlled from the exterior of the jaw, and sufficient loosening of this screw permits of the withdrawal or removal of the spring, the free end of which normally 95 would engage the shoulder 4 and prevent separation of the movable jaw from the shank of the fixed jaw, but when this spring is removed the movable jaw can be removed, and again replaced, or a new one if necessary put in position, the spring inserted and secured by the 100 screw. The opposite side of the movable jaw is recessed, as shown at 19, and within this recess is the guide and stop pin 20, integral with the jaw, as seen in Fig. 3 and which serves an important function in the operation of the wrench, as will soon be described. A 105 space or opening 21 is provided between the acting face

of the movable jaw and the adjacent face of the shank portion 2, as seen best in Fig. 2, to permit of the necessary rocking movement of the movable jaw.

- As will be seen from Fig. 2, a line drawn through the 5 acting portion of the pin 20 and face 22 will be parallel with the face 10, and the distance between this line and the said face 10 will be the same as the distance from side to side of the portion 2 of the shank. By this means when the parts are in the position shown in Fig. 10 2, the movable jaw is locked and any strain or pressure upon its acting face only tends to more securely hold it against movement because the greater the strain or pressure the more firmly will the faces 10 and 22, and the pin 20 be held against the shank portion 2.
- 15 The mode of use will be apparent. Pressure with the thumb upon the concave portion 23 of the movable jaw, which concaved portion being preferably serrated, as shown, to provide better frictional engagement of the thumb, serves to rock the movable jaw, when the latter 20 can be easily moved by the thumb in either direction. The tapered space between the acting faces of the two jaws serves to afford a better hold upon the nut or other article and compensates for any lost motion there may be in the movable jaw.
- 25 The disposition of the parts whereby the parallelism of the faces 10 and 22 and the pin 20 is maintained to constitute a rigid lock for the movable jaw when the teeth are in engagement is of prime importance.
- 30 ~~Modifications in detail may be resorted to without de-~~ 35 parting from the spirit of the invention or sacrificing any of its advantages.

What I claim as new is:—

1. In a wrench, a stationary jaw and its shank, and a movable jaw on said shank, the coöperating faces of the 35 movable jaw and shank being toothed, the said movable jaw being recessed and provided with a guide and locking pin, the opposite acting faces of the movable jaw and the

acting face of said pin being parallel, whereby when they are in engagement with said shank the movable jaw is locked against movement.

2. In a wrench, a stationary jaw and its shank, and a movable jaw on said shank, the said movable jaw being recessed and provided with a guide and locking pin, the opposite acting faces of the movable jaw and the acting face of said pin being parallel, whereby when they are in engagement with said shank the movable jaw is locked against movement, one of said acting faces of the movable jaw being toothed to engage coöperating teeth on said shank.

3. In a wrench, a stationary jaw, its shank having a rectangular portion with one face provided with fine teeth, and a movable jaw having acting faces parallel with said shank, and a guiding and locking pin, the said pin and one acting face of the jaw being parallel with the other acting face, the distance between them being the same as the width of the rectangular portion of the shank, said movable jaw being mounted for rocking movement on said rectangular portion.

4. In a wrench, a stationary jaw having a beveled acting face, the shank of said jaw, a movable jaw on said shank, the said movable jaw being recessed and provided with a guide and a locking pin and with a right angled acting face, the opposite acting faces of the movable jaw and the acting face of said pin being parallel with each other and with the faces of said shank, whereby when they are in engagement with said shank the movable jaw is locked against movement.

5. In a wrench, a shank and a stationary jaw thereon, a movable jaw mounted for rocking movement on said shank and having a chamber with abutment, a spring in said chamber with one end seated on said abutment, and a screw adjustable in said jaw with one end bearing against the end of the spring and securing it to said abutment, the other end of said screw being accessible from the outside of said jaw.

Signed by me at Reading Penna. this 1st day of February 1907.

MAX SCHWENDNER.
